DENTAL IMPLEMENT

Gunnar Bergendal, Angby, near Stockholm,
SwedenApplication May 6, 1949, Serial No. 91,786
In Sweden May 19, 1948

1 Claim. (Cl. 32—59)

1

This invention relates to dental implements, and particularly to grinding tools for use in preparing teeth for the application of artificial crowns thereon.

One object of the invention is to provide such a tool which enables the dentist to perform the work referred to exactly and rapidly.

A further object of the invention is to provide such a tool which is self-guiding during use.

Another object of the invention is to provide such a tool which automatically prevents grinding beyond any desired limit.

Still another object of the invention is to provide such tool which cannot hurt either the patient's soft mouth parts or teeth adjacent to the one undergoing work.

To the accomplishment of the foregoing and other objects the invention consists of the structure hereinafter described and pointed out in the appended claim, the annexed drawing and the following description setting forth in detail a structural embodiment, such disclosed structure constituting one of the many forms in which the principles of the invention may be realized.

In said drawing:

Fig. 1 is a side elevation of an embodiment of the invention.

Fig. 2 is a left-hand end view of the tool shown in Fig. 1.

Fig. 3 illustrates diagrammatically the use of the form of tool shown in Figs. 1 and 2, said tool and the tooth undergoing preparation being both shown in side elevation.

Figs. 1 and 2 show a grinding disk 1 provided with a shaft 2 at right angles to the plane of said disk and with an abrasive 3 at one end face thereof. The characteristic feature of this form of my invention is that the circumference of the grinding disk 1 and an annular zone internally thereof are not provided with abrasive for the purpose of forming a stop member or feeler 4 rotating with the grinding disk 1. As may be seen more clearly from Fig. 2 the abrasive 3 is countersunk so as to be substantially flush with the adjacent plane breast face 5 of the flange 4 and besides the latter is rounded off as shown to avoid sharp edges.

Figs. 1 and 2 show a cylindrical grinding wheel 1 provided with an abrasive 3 at its circumference and at one of its end faces whereas its opposite end face is united to a smooth disk 4 the diameter of which is somewhat larger than that of the grinding wheel proper. As will appear from the following the smooth flange 5 of the disk 4 situated externally and laterally of the grinding wheel 1 forms a stop member or guide rotating with the grinding wheel 1 so as to facilitate the shaping of a shoulder in preparing a tooth to be provided with a jacket crown. The smooth rigid disc is concentrically mounted on a spindle

2

shaft 2 and the grinding wheel is also concentric with the smooth disc and said shaft.

The advantages resulting from the use of my present improved dental implement will clearly appear from a study of Fig. 3.

In using the tool illustrated in Fig. 3 the dentist works his way downwardly and inwardly by means of the grinding wheel 1 and then the smooth guide flange 5 when entering the gums pocket, stops the tool whereby the correct position of a shoulder 7 in vertical direction is secured. Simultaneously the guide 5 prevents the dentist from working his way too far into the teeth. With this guide or stop member omitted it might happen that the dentist even if he works very cautiously would grind off the tooth too much both vertically and horizontally in shaping the shoulder 7. Thus, the guide 5 forms a simple but efficient means for facilitating the preparatory work referred to and permits the dentist to work more safely and rapidly in shaping the shoulder.

From the foregoing it may be seen that by my present invention I have provided a grinding tool for dental use which although of very simple design greatly facilitates the tooth preparation referred to and effects so to speak a positive control of the tool by means of the smooth non-grinding stop member or guide rotating with the grinding tool proper. Nor will this smooth and noncutting member hurt any soft parts during use.

What I claim is:

A dental grinding tool for external work on teeth comprising a rigid circular disc rotatable about an axis at right angles to the plane thereof, said disc having a cylindrical disc of abrasive material permanently coaxially secured to one face thereof, and said disc of abrasive material being of smaller diameter than the first mentioned disc, the edge portion of said first disc extending radially outwardly from immediately adjacent the cylindrical abrasive disc and said edge portion being smooth and continuous so as to serve in use as a guide which performs no abrading action.

GUNNAR BERGENDAL.
